DESIGN FOR A SMOKER'S PIPE RACK

Edward A. Rosenbaum, Milwaukee, Wis.

Application April 16, 1947, Serial No. 138,427

Term of patent 3½ years

(Cl. D85—8)

To all whom it may concern:

Be it known that I, Edward A. Rosenbaum, a citizen of the United States, residing at Milwaukee, in the county of Milwaukee and State of Wisconsin, have invented a new, original, and ornamental Design for a Smoker's Pipe Rack, of which the following is a specification, reference being had to the accompanying drawing, forming part thereof.

In the drawing:

Fig. 1 is a side view of a smoker's pipe rack, showing my new design.

Fig. 2 is a top plan view thereof.

I claim:

The ornamental design for a smoker's pipe rack, substantially as shown.

EDWARD A. ROSENBAUM.
